ATTORNEY

UNITED STATES PATENT OFFICE.

ALBERT MALSIN, OF NEW YORK, N. Y.

ARCH SUPPORT.

Application filed August 7, 1922. Serial No. 580,083.

To all whom it may concern:

Be it known that I, ALBERT MALSIN, a citizen of the United States of America, residing at New York, in the county of New 5 York and State of New York, have invented certain new and useful Improvements in Arch Supports, of which the following is a specification.

This invention relates to arch supports 10 and has for its object to provide a construction whereby the effectiveness and usefulness of the arch support will be greatly enhanced.

An arch support as heretofore constructed is made of a curved resilient plate and is 15 embedded between the insole and outsole of the shoe below the arch. Its usefulness as a support is, however, hardly felt, as it readily yields under the weight of the wearer. Furthermore, whatever little support it may at first lend to the arch is lost 20 after a short time of use because of its tendency to flatten as a result of the gradually weakening resiliency.

According to my invention the arch support 25 port is provided with means which will obviate these drawbacks and which, moreover, will have the effect of a strongly resisting pressure on the support, but in a yielding manner, so that the arch support will 30 not be felt uncomfortable.

My invention will be more clearly understood by reference to the accompanying drawing in which similar reference characters denote corresponding parts and in 35 which Fig. 1 is a bottom plan view of a shoe with the outsole and heel removed to show my new arch support; Fig. 2 is a longitudinal section on line 2—2 of Fig. 1 and Fig. 3 is a cross section on line 3—3 of 40 Fig. 1.

10 denotes the shoe, 11 the insole, 12 the outsole and 13 the heel of a shoe. The arch support, as usual, is adapted to be embedded between the soles under the arch of the shoe.

45 According to my invention the arch support comprises three spring members 14, 15 and 16. The main member 16 is a metal plate substantially of the usual construction and shape and adapted to be mounted between the inner faces of the two soles, so 50 that its rear end will slightly project into a cavity 13' made in the upper face of the heel.

The two other spring members 14, 15 are 55 in form of arched metal plates, of which one, 14, is inserted between the two soles, so

that its arched portion 14' will spread the two soles apart a short distance of their length, and the other 15 is positioned in the cavity 13' of the heel 13. The two 60 spring members 14, 15 are suitably fixed in position at their outer ends by screws 17 or the like, while their inner ends are loose and capable of compression and expansion in longitudinal direction. The arched portion 15' having merely the function to lend resiliency to the plate 15 is directed with its convex face downwardly into the cavity 13' to be free to expand and contract. The arched portion 14' of the member is directed 65 with its convex surface upwardly to bear against the inner face of the insole so that in addition to its function as a spring it will, during walking, while expanding and contracting, as will be presently explained, 70 exercise a massaging action on the sole of the foot.

The inner ends of the members 14, 15 are bent laterally upon themselves, as at 14², 15² to form sockets for engaging the 80 opposite ends of the main plate 16 which are adapted to project through said sockets and to bear against the arched portions 14', 15'.

As a result of this construction, when the 85 main spring plate 16 under the weight of the wearer will tend to flatten its ends will act against the arched portions 14', 15' which in their turn will exert a strong but yielding resistance. Thereby the resiliency 90 of the main plate will be not only sustained, but even strengthened and its effectiveness as arch support greatly enhanced. During walking the alternate compression and expansion of the arch portion 14' caused by 95 the corresponding functioning of the main plate 16 will produce a slight massaging action on the sole of the wearer's foot, which will have the beneficial effect of strengthening the muscles of the latter.

100 It is obvious that various changes may be made in the construction without departing from the principle of my invention, and I, therefore, do not wish to restrict myself to the details described and shown.

105 What I claim is:—

1. In a shoe having a cavity in its heel, an arch support comprising a resilient member extending longitudinally between the insole and outsole of the shoe and projecting 110 at its rear into said cavity, and two resilient arched members, one fixed at its front end

between said soles and the other, at its rear end in said cavity, the free ends of said arched members being formed with sockets to slidably engage the ends of said first member and the arches of said members being adapted to act against the same to prevent flattening of said first named member.

2. In a shoe having a cavity in its heel, an arch support comprising a resilient member extending longitudinally between the insole and outsole of the shoe and projecting at its rear into said cavity, and two resilient arched members, one fixed at its front end between said soles and the other, at its rear end in said cavity, the free ends of said

arched members being formed with sockets to slidably engage the ends of said first named member and the arches of said members being adapted to act against the same to prevent flattening of said first named member, 20 the arch of the front member being directed upwardly so as to also act as a massaging element.

In testimony whereof I affix my signature in presence of two witnesses.

ALBERT MALSIN.

Witnesses:

MAX D. ORDMANN,
THELMA BUETTNER.
